John A. Herrod, Fountain Valley, Calif. (1970 16th
St., Apt. N103, Newport Beach, Calif. 92660)

Filed June 6, 1974, Ser. No. 477,004

Term of patent 14 years

Int. Cl. D12—16

U.S. Cl. D12—181

FIG. 1 is a perspective view of a stabilizer vane showing my new design, it being understood that the broken lines are for illustrative purposes only;

FIG. 2 is a top plan view thereof to an enlarged scale;

FIG. 3 is a side elevational view thereof to an enlarged scale;

FIG. 4 is an end elevational view thereof to an enlarged scale; and

FIG. 5 is a bottom plan view thereof to an enlarged scale.

The stabilizer vane has been broken away in the center in FIGS. 2, 3 and 5 for convenience of illustration.

I claim:

The ornamental design for a stabilizer vane, as shown and described.
